(57) CLAIM

The ornamental design for a modular staff, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top front perspective view of a modular staff showing my new design;

FIG. 2 is bottom rear perspective view thereof;

FIG. 3 is a left elevated view thereof;

FIG. 4 is a right elevated view thereof;

FIG. 5 is a front elevated view thereof;

FIG. 6 is a rear elevated view thereof;

FIG. 7 is an enlarged top plan view thereof; and,

FIG. 8 is an enlarged bottom plan view thereof.

FIG. 9 is an exploded front elevational view thereof; and, FIG. 10 is a magnified front elevational view thereof.

The broken lines depict the locations of magnified views and borders of magnified views, and form no part of the claimed design.
